UNITED STATES PATENT OFFICE.

ALEXANDER BERNHARD DRÄGER, OF LÜBECK, GERMANY.

MULTIPLE-WAY FIXTURE FOR CONNECTING A PLURALITY OF PIPES.

Application filed July 18, 1924. Serial No. 726,890.

To all whom it may concern:

Be it known that I, ALEXANDER BERNHARD DRÄGER, a German citizen, residing at Lübeck, Germany, have invented certain

5 new and useful Improvements in Multiple-Way Fixtures for Connecting a Plurality of Pipes, of which the following is a specification.

10 The present invention relates to a multiple way fixture for connecting a plurality of pipes, as used particularly in breathing apparatus, and described in my prior patent application Ser. No. 476,238 filed June 9th 1921. The multiple way fixture disclosed 15 by this prior application consists of two integral sections extending transversely to each other and provided with bores extending at approximately right angles to each other in different planes and each connected 20 with one of said pipes, said fixtures further having a connecting channel extending between said bores to connect the same, and a valve in one of the sections of the said fixture for controlling the communication between said bores.

25 The novel feature of the improved fixture forming the subject-matter of the present invention, consists in that from the valve chamber of the section containing the valve 30 for controlling the communication between the bores of this section and the main section, is branched off a third integral section the bore of which is in connection with a further pipe and controlled by a suitable, 35 preferably a self-closing stop valve. The arrangement being thus that the bore of the third section also after closing the controlling valve of the bore of the second or transverse section remains always in communication 40 with the bore of the main section, so that after opening the controlling valve of the third section communication is established between the bore of the main section and the pipe connected to the third section. 45 By means of the improved fixture it is therefore possible to tap or draw off any fluid from the main section to and through the third section, even if the second or transverse section has been shut off.

50 In the accompanying sheet of drawings is shown an example of the improved fixture constructed in accordance with and embodying the present invention. Fig. 1 is an elevation of the improved fixture in connection with the pipes of a self-contained breathing apparatus of which is shown only

as much as is necessary for the understanding of the invention; Fig. 2 is a section on the line A—B of Fig. 1; and Fig. 3 is a section on the line C—D of Fig. 2.

60 Similar letters of reference refer to like parts throughout the several views.

The fixture consisting of three integral sections, the main section *a*, the second or transverse section *c* and the third or auxiliary section *k*, is situated between the stop valve *e* of the oxygen container *f* and the pressure reducing valve *v* of a self-contained breathing apparatus. In Fig. 1 the controlling valve *g v* of the second or transverse section *c* (see Fig. 2) is in the opened position, its operating lever *h* being capable of being secured in this opened position against unintentional turning by fastening it to a suitable stop *i* or the like attached to the casing of the pressure reducing valve *b*.

70 By turning down the lever *h* from the upright position (Fig. 1) into the horizontal position (Fig. 2) the controlling valve *g v* will be closed and the communication between the bores of the sections *a* and *c* cut off.

75 From the valve chamber *v*¹ of the second section *c* the bore of which is transverse to the bore of the main section *a*, both bores extending at about right angles to each other in different planes and being in communication by a connecting bore *d*, is branched off a likewise integral third section *k*. The outlet end of the bore of this 80 third or auxiliary section *k* is held closed preferably by a self-closing valve consisting of a spring actuated bent lever *p* adapted to be operated in well known manner by means of a press-button *o* gas-tightly and 85 movably arranged in the framing of a window in the wall of a suitable cap *m* screwed upon the said section *k* and protecting the valve mechanism *p* within the said cap *m* against influences from without. From the 90 cap *m* a discharge socket *n* branches off.

95 When the valve *e* of the oxygen container *f* and the valve *v* of the transverse section *c* are opened (Fig. 1), high pressure oxygen is passing through the main section *a* into the pressure reducing valve *b* from where 100 low pressure oxygen for revivifying the breathing air is continuously passed through the pipe *g* into the air circuit-system of the breathing apparatus in a predetermined constant amount per unit of time. Besides 105 this constant amount of oxygen per unit 110

of time additional low pressure oxygen may be periodically supplied by means automatically operated by inspirations, said means being disclosed for example in my prior 5 patent application Ser. No. 601,030 filed Nov. 15th, 1922, from the pressure reducing valve through the pipe r to the air circuit system in accordance with the breathing requirements prevailing at the time. A 10 part of the oxygen flowing through the main section a , is passing through the connecting bore d and the valve chamber v^1 also into the bores of the sections c and k and filling them up. As the section c is 15 connected to a by-pass conduit s for the pressure reducing valve b , said conduit s leading to the pipe q and being provided with a hand operated controlling valve for example of the kind as fully disclosed in 20 my prior patent application Ser. No. 476238, filed June 9th 1921, additional high pressure oxygen may be periodically supplied through the pipe q into the air circuit system of the breathing apparatus by opening the valve controlling the said by-pass conduit. No high pressure oxygen can discharge through the third section k as long 25 as its bore is kept closed by the controlling valve p .

If for any reason the by-pass conduit s has become unavailable for supplying additional high pressure oxygen, the transverse section c is closed by screwing home the controlling valve v (Fig. 2). In order 30 to supply nevertheless additional high pressure oxygen into the air circuit system of the apparatus it, requires only a short opening of the controlling valve p by gently touching or pressing on the press-button o (Fig. 3). Oxygen is then passing at once 35 through the bore of the section k into the interior of the cap m and from here through the socket n , the pipe t (Fig. 1) and the by-pass conduit s into the pipe q and the 40 air circuit system of the apparatus respectively. The additional supply of oxygen 45 ceases, as soon as the press-button o is released and the valve p under the action of the spring p^1 automatically closes the bore 50 of the section k .

I claim:

1. A multiple way fixture for connecting a plurality of pipes, consisting of three

integral sections, the first and second of them extending transversely to each other 55 and provided with bores extending at approximately right angles to each other in different planes and each adapted for connection with separate pipes, said fixture further having a connecting channel extending between said bores to connect the same, a valve in said fixture for controlling the communication between said bores, the third section extending from the second section at about right angles and provided 60 with a bore emanating from the valve chamber of the second section, and a valve controlling the bore of the third section.

2. A multiple way fixture for connecting a plurality of pipes, consisting of three integral sections, the first and second of them extending transversely to each other and provided with bores extending at approximately right angles to each other in different planes and each adapted for connection with separate pipes, said fixture further having a connecting channel extending between said bores to connect the same, a valve in said fixture for controlling the communication between said bores, the third section extending from the second section at about right angles and provided 70 with a bore emanating from the valve chamber of the second section, a cap extending over said third section, a self-closing valve 75 mechanism mounted within said cap and controlling the bore of the third section, and a press-button for actuating said valve mechanism to open the valve.

3. A multiple way fixture comprising a 90 casing having first, second, and third bores in communication with each other, the exit end of the first bore being arranged to lead to one point and the second and third bores being arranged to lead to a common 95 point different from the point to which the first bore leads, a first valve in said casing controlling the communication between said first and second bores and a second valve controlling the communication between the third bore and the point to which it leads, said second valve being operated, 100 at will, to open said communication even when said first valve is closed.

ALEXANDER BERNHARD DRÄGER.
